Attn:

UNITED STATES PATENT OFFICE

JOHANN EHRLICH, OF VIENNA, AUSTRIA

STAND FOR THE DISPLAY OF GOODS

Application filed September 22, 1930, Serial No. 483,695, and in Austria October 3, 1929.

Stands for the display of goods are known in which the plates, wire hooks and the similar devices carrying the goods are clamped between two rings each movable along a post. 5 The post is provided for its whole length with screw thread and the clamping rings are formed into screw nuts so as to move up and down along the post when turned. These display stands are suffering under the 10 drawback that the costs of production are high and that the operation of displacing the clamping rings is complicated and takes much time.

According to the present invention these 15 disadvantages are eliminated by providing the post only at its upper and lower end with screw threads, leaving it smooth for nearly the whole length and by employing a spring for pressing together the clamping rings, 20 which are loosely displaceable on the post, the pressure of this spring being easily overcome whenever two neighbouring rings are to be moved asunder for taking up an object to be clamped in between.

25 An embodiment of this invention is illustrated by way of example in the accompanying drawing which gives a side view and, in part, an axial section.

The stand consists of a smooth post 2 which 30 at its bottom end is screwed into a foot plate 1, the post being provided with a screw thread above and below. A cap 3 can be screwed on the top end. The smooth post carries loosely displaceable rings 4, the bottom one 35 of which is in contact with a tube piece 5 that is displaceable in a wider tube piece 6 resting on the foot plate 1. Within the two tube pieces 5, 6 there is a helical spring 7, which presses the tubular piece 5 upwards 40 so that the displaceable rings lying one above the other are elastically supported by the spring. On one of their borders the rings 4 are provided with annular recesses 8 which permit the introduction of the short arms 9 45 lying on each other of a tong-like tool acting in the manner of a glove extender. By compressing the long arms 10 of this tool the pressure of the spring 7 is overcome and the neighbouring rings are moved asunder. Into 50 the free space formed between the rings in

this manner, a plate 11, a hook 12 or any other object may be introduced. If, then, the hand ceases to press on the long arms 10 of the tool, the spring 7 begins to act so that the rings will fix in its position the object 55 introduced.

Having now particularly described and ascertained the nature of my said invention and in what manner the same is to be performed, I declare that what I claim is:

1. A display stand comprising a base, a rod supported by said base, a fixed cap upon the upper end of said rod, a plurality of clamping rings slidably mounted upon said rod between said cap and said base, resilient means 60 cooperating with said base urging said clamping rings against said cap and detachable display supporting elements supported between adjacent clamping rings. 65

2. A display stand comprising a base, a rod supported by said base, a cap fixed upon the upper end of said rod, a plurality of clamping rings loosely displaceable upon said rod, a spring cooperating with said base 70 urging said rings against said cap and detachable display supporting elements supported between adjacent rings. 75

3. A display stand comprising a base, a rod supported by said base, a fixed abutment upon said rod, a plurality of clamping rings slidably mounted upon said rod between said abutment and said base, a telescoping housing positioned upon said rod between said rings and said base and resilient means in 80 said housing tending to expand the same and to urge said rings against said abutment. 85

4. A display stand comprising a base, a rod supported by said base, a fixed abutment upon said rod, a plurality of clamping rings 90 slidably mounted upon said rod between said abutment and said base, said rings being provided with recesses to permit the introduction of a tool for separating adjacent rings apart, resilient means urging said clamping rings together and detachable display supporting elements supported between adjacent 95 clamping rings.

In testimony whereof I have affixed my signature.

JOHANN EHRLICH. 100
